UNITED STATES PATENT OFFICE.

ARCHIBALD B. MCNEIL, OF ATLANTIC, IOWA.

DESIGN FOR A PUZZLE-BOARD.

SPECIFICATION forming part of Design No. 30,211, dated February 14, 1899.

Application filed January 21, 1899. Serial No. 702,989. Term of patent 3½ years.

To all whom it may concern:

Be it known that I, ARCHIBALD B. MCNEIL, a citizen of the United States, residing at Atlantic, in the county of Cass and State of Iowa, 5 have invented and produced a new and original Design for a Puzzle-Board, of which the following is a specification.

This invention relates to a new and original design for a puzzle-board; and it has for 10 its object to provide a design of this character that shall be both useful and ornamental.

The leading feature of the design resides in a puzzle-board having a flat playing-surface provided thereon with a plurality of open 15 circular pens spaced apart and arranged in alignment in a common plane.

While the essential feature of the design resides in a board provided with a plurality of open circular pens or figures spaced apart 20 and transversely alined, the invention involves several minor features, which are the puzzle-board being of a rectangular shape and provided with a peripheral upstanding flange, said puzzle-board having three of the circular pens or figures, which are disposed in trans- 25 verse alinement.

Additional minor features of the design are the three circular pens or figures being provided in their contiguous sides with openings 30 leading within the pens and lying in a plane intersecting the centers of all of said pens, each of the pens being further provided at diametrically opposite points with similar openings lying in a plane at right angles to the plane of the other openings.

In the drawings, Figure 1 is a perspective

view of a puzzle-board embodying the herein-described design. Fig. 2 is a top plan view thereof.

Referring to the accompanying drawings, 40 the numeral 1 designates the rectangular board-body, provided at its upper side with a flat playing-surface 2 and surrounded by a peripheral upstanding flange 3. Upon its flat playing-surface 2 the board-body 1 is provided with three circular pens or figures 4, spaced a distance apart from each other and arranged in transverse alinement, the centers of all of the said circular pens or figures being intersected by a line passing through the 45 center of the board 1. The several circular pens or figures 4 are provided in their contiguous sides with openings 5, leading into the central open space of the pens or figures and lying in a plane intersecting the centers 50 of the same. Each of said circular pens or figures 4 is further provided in diametrically opposite sides with oppositely-located openings 6, which also lead into the central open spaces of the pens or figures and lie in a plane 55 disposed at right angles to the plane of the other openings 5.

What is claimed is—

The design for a puzzle-board, herein shown and described.

In testimony that I claim the foregoing as my own I have hereto affixed my signature in the presence of two witnesses.

ARCHIBALD B. MCNEIL.
